[57] CLAIM

The ornamental design for a steam cover for culinary vessels, as shown.

DESCRIPTION

FIG. 1 is a front elevational view of a steam cover for culinary vessels showing my new design;

FIG. 2 is a rear elevational view thereof;

FIG. 3 is an elevational view thereof as viewed from the left side;

FIG. 4 is a top plan view thereof;

FIG. 5 is a bottom view thereof; and

FIG. 6 is an enlarged scale sectional view taken along line 6—6 of FIG. 3.

FIG. 1

FIG. 4

FIG. 2

FIG. 5

FIG. 3

FIG. 6
